Primary Examiner — Dana L Meyrow(74) *Attorney, Agent, or Firm* — Henry J. Cittone; Cittone & Chinta LLP(57) **CLAIM**

The ornamental design for a bottle, as shown and described.

DESCRIPTION

FIG. 1 is a front elevational view of a bottle showing my new design;

FIG. 2 is a rear elevational view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a top, front, right side perspective view thereof.

The broken line showing of the vertical sidewall details is for the purpose of illustrating the article and forms no part of the claimed design.
